CLAIM

We claim, the ornamental design for a sculpture, scale model sculpture, sculpture replica, and/or other replicas, as shown and described.

DESCRIPTION

FIG. 1 is a perspective view of a sculpture, scale model sculpture, sculpture replica, and/or other replicas, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a cross-sectional view of FIG. 5;

FIG. 8 is an enlarged perspective view of a portion thereof;

FIG. 9 is an enlarged perspective view of a portion thereof;

FIG. 10 is an enlarged perspective view of a portion thereof;

FIG. 11 is an enlarged perspective view of a portion thereof; and,

FIG. 12 is a sectional top plan view thereof.

1 Claim, 12 Drawing Sheets
